UNITED STATES PATENT OFFICE.

THOMAS F. KRAJEWSKI, OF NEW YORK, N. Y.

PORTABLE RAILWAY-TRACK.

SPECIFICATION forming part of Letters Patent No. 235,786, dated December 21, 1880.

Application filed August 4, 1880. (No model.)

To all whom it may concern:

Be it known that I, THOMAS F. KRAJEWSKI, of the city, county, and State of New York, have invented a certain new and useful 5 Improvement in Portable Railway-Tracks, of which the following is a specification.

In a portable railway-track it is of great importance that the rail-sections should be so joined together that vertical and lateral movement of one section independent of the adjacent section will be prevented; and it is also of great importance that the joints between the sections should be so constructed that the sections can all be readily detached from each 15 other and taken up when it is desired to move the track, or so that one section can be taken up and readily replaced by another, which may be a switch, a crossing, or a frog.

My invention consists in the combination, 20 with the abutting ends of two adjacent rail-sections in a portable railway-track, of two fish-plates secured one to the rail and cross-bar of one section upon one side of the rail and the other to the rail and cross-bar of the 25 other section upon the other side of the rail, each fish-plate projecting beyond the end of the rail-section to which it is secured and overlapping and bearing against the rail and cross-bar of the other section, but otherwise 30 having no connection therewith.

In the accompanying drawings, Figure 1 represents a plan of a portion of a portable railway-track embodying my invention. Fig. 2 represents a side view of one of the fish-joints of said track upon a larger scale. Fig. 3 represents a transverse section upon the dotted line *x x*, Fig. 2, and Fig. 4 represents a partly-sectional plan of the joint.

Similar letters of reference designate corresponding parts in all the figures.

A A' designate adjacent sections of rail, which are placed end to end, and the abutting ends of which are to be united. The rails of the sections are secured in the usual manner 45 by bolting or riveting to cross-bars. The end cross-bars, B B', are placed in close proximity to the joint, and secured to the rails by being bolted or riveted to the angle fish-plates C C', which are also bolted or riveted to the rails, 50 as clearly shown in the drawings.

As clearly shown, the fish-plates C are se-

cured to the rails A and cross-bar B, and the fish-plates C' to the rails A' and cross-bar B' by means of bolts, or permanently secured thereto by means of rivets *b*, as here shown. 55 The fish-plates secured to the ends of one track-section overlap and bear against the rails and the cross-bar of the other section, but otherwise have no connection therewith, thus transmitting the pressure from one section directly to the rail and cross-bar of the following section.

In order to enable a rail-section to be easily disconnected from a line of connected sections by simply raising it at the joint, I preferably 65 make the projecting ends of the fish-plates inclined or slanted on their upper or top edges, as clearly shown at *c* in Fig. 2.

In order to provide for laying straight sections of track around a curve, the projecting 70 ends of the base or horizontally-extending portion of each fish-plate is slanted or flared outwardly, as shown particularly at *e* in Fig. 4, so as to permit the adjacent rails to be laid at a slight angle to each other.

It will be also noticed that while the fish-plate at one end of the rail-section is secured to the inner side of the rail, that of the abutting rail of the following section is secured on its outside, as shown in Figs. 1 and 4. 80 This arrangement, which has been called out by this special manner of joining the sections, has this advantage, that the pressure of one section upon the other is transmitted alike—that is, by means of a fish-plate pressing upon 85 the rail and cross-bar, there being no difference whether this action is on the outside or inside of the rail.

It will be seen that by my invention I provide for making a strong yet flexible joint 90 for portable track-sections, the angle fish-plate being itself a strong form of joint, and which, being secured between the head of the rail and its flange, relieves the rivets from the greatest portion of strain on them, and admits 95 at the same time of securing solidly the cross-bar to the rail, which otherwise is not easy to effect on account of the small dimensions of the rail.

What I claim as my invention, and desire to 100 secure by Letters Patent, is—

The combination, with the abutting ends of

two adjacent rail-sections in a portable rail-way-track, of two fish-plates secured one to the rail and cross-bar of one section upon one side of the rail and the other to the rail and cross-bar of the other section upon the other side of the rail, each fish-plate projecting beyond the end of the rail-section to which it is secured and overlapping and bearing against

the rail and cross-bar of the other section, but otherwise having no connection therewith, substantially as and for the purpose specified.

THOS. F. KRAJEWSKI.
